CLAIM

The ornamental design for a storage container, as shown and described.

DESCRIPTION

FIG. 1 is a front elevational view of the storage container showing my new design;

FIG. 2 is a top plan view of the storage container shown in FIG. 1;

FIG. 3 is a rear elevational view of the storage container shown in FIG. 1;

FIG. 4 is a right side elevational view of the storage container shown in FIG. 1, the left side elevational view being a mirror image thereof; and,

FIG. 5 is a perspective view thereof.

The bottom of the storage container is plain and unornamented.
